UNITED STATES PATENT OFFICE

171,588

MOTOR VEHICLE

Herman C. Frank, Billings, Mont.

Application November 28, 1952, Serial No. 22,487

Term of patent 14 years

(Cl. D14—3)

To all whom it may concern:

Be it known that I, Herman C. Frank, a citizen of the United States, residing at Billings, in the county of Yellowstone and State of Montana, have invented a new, original, and ornamental Design for a Motor Vehicle, of which the following is a specification, reference being had to the accompanying drawing, forming part thereof.

Figure 1 is a side elevational view of a motor vehicle, showing my new design;

Figure 2 is a top plan view thereof;

Figure 3 is a front end view, and

Figure 4 is a rear end view of the same.

I claim:

The ornamental design for a motor vehicle, as shown.

HERMAN C. FRANK.
